VENDING MACHINE

Walter A. Tratsch, Chicago, Ill.

Application October 14, 1937, Serial No. 168,982

4 Claims. (Cl. 312—97)

This invention is concerned with improvements in vending machines, and has among its principal objects the provision of such a machine particularly adapted to vend packaged articles, such as candy bars and the like.

A further object of the invention is the provision of a vending machine of increased storage capacity and adapted to position one packaged item in view at a time.

10 Another object is the provision of a vending machine provided with a cabinet having a sight opening disposed at the eye level and movable means for maintaining a quantity of packaged items in columnar form with the topmost package in view before the eye level sight opening.

Still another object is the provision of coin actuated motor driving mechanism for ejecting the topmost article from the column and thereafter raising the column a distance of one package responsive to the deposit of a coin.

20 Yet another and more particular object is the provision of a vending machine including a cabinet adapted to extend from the floor level to a height at or above the average eye level and having a sight opening in its upper portion at the eye level, and a substantially vertically extending conveyor member adapted to hold a plurality of packaged articles in columnar arrangement and dispose the topmost package before the sight opening, together with automatic coin operated control mechanism including an ejector for displacing the topmost package for movement into a discharge opening and move the column upwardly a distance to dispose another package before the sight opening.

25 A still further object is the provision of a simplified sprocket gear driving mechanism for the ejector and column moving means, as well as automatic circuit control mechanism actuated by a deposited coin to start the motor and drive the sprocket mechanism through a cycle of operation and thereafter stop the motor.

Other novel aspects of the invention both in construction and operation will appear as the following description develops in view of the drawings in which:

30 Fig. 1 is a front elevation of the vending machine cabinet;

Fig. 2 is an enlarged vertical section through the cabinet along lines 2—2 of Fig. 1;

Fig. 3 is a circuit diagram;

Fig. 4 is an enlarged fragmentary rear elevation of the upper sprocket and column mechanism viewed along lines 4—4 of Fig. 2;

Fig. 5 is a side view of the structure of Fig. 4 viewed in the direction of lines 5—5 thereof;

Fig. 6 is a fragmentary horizontal sectional detail of the lower sprocket and column drive mechanism as viewed along lines 6—6 of Fig. 2, 5 and is turned 180 degrees with respect to the showing in Fig. 2;

Fig. 7 is a side elevation of the mechanism of Fig. 6 as viewed along lines 7—7 thereof; while

Fig. 8 is a side elevation of the mechanism 10 of Fig. 6 as viewed along line 8—8 thereof.

In accomplishing the several objects of the invention, I provide in one embodiment an upstanding cabinet 10 with a front panel 11 having a sight opening 12 disposed in the upper portion 15 thereof substantially at the average eye level. If desired, the sight opening 12 may extend downwardly to provide a space for instruction cards 13 or the like, there being, of course, a glass panel closing the opening. At the lower end of the 20 sight opening there is disposed a discharge outlet 14 into which the merchandise is deposited in a manner hereinafter to be described.

In the form of device shown herein, the discharge outlet 14 may desirably form part of a 25 mounting plate 15 in which are disposed a plurality of coin deposit openings 16, each positioned substantially before a corresponding column 17 of merchandise. Below the mounting plate 15 is a removable panel or door 18 in the face of which 30 is disposed a coin return cup 19, the panel being locked in position.

35 Interiorly of the cabinet, as viewed in Fig. 2, there is arranged a metal apron having a lower portion 20 fixed behind the inside of the door 18 and an intermediate portion 21 extending diagonally upwardly to the lower margin of the eye level, opening where it is turned back upon itself to provide a discharge chute portion 22 terminating at its lower end in the discharge outlet 40 or cup 14, one article of merchandise 17' being normally positioned at the upper edge 22' of this discharge chute from which position the article is ejected or dislodged by a special ejecting mechanism, which includes a top ejector bar 23, having 45 depending fingers 23', and which is attached at one end 24 (Fig. 4) to a vertical arm 25 pivotally mounted, as at 26, on a bracket member 27 attached to the inner top wall of the cabinet.

At its lower end the vertical ejector mounting 50 bar 25 is provided with a small roller 28 adapted to be engaged by a cam finger 29 mounted on a sprocket sleeve 30 which in turn floats on a shaft 31 supported within the upper portion of the cabinet below the sight opening. Thus the 55

ejector cam 29 is adapted to pivot the ejector bar 28 once during each revolution into the dotted line position seen in Fig. 5, which movement is sufficient to dislodge the topmost package 17' from the column and cause the same to gravitate over the upper edge 22' of the chute 22 down into the receptacle 14. At the conclusion of each ejecting stroke, the ejector 23 is returned to normal position by means of a spring 32.

10 The means for disposing the packaged items in a column is a conveyor which includes pivoted shelves 33 each of a width corresponding substantially to the width or length of the merchandise package, and each being pivotally attached, 15 as at 33', at their sides to spaced sprocket chains 34 which are trained over upper idling sprockets 35 mounted on shaft 31, and at their lower end over special timing sprockets 36 which float on a pin 70 supported in a bracket 71 on the floor 20 of the cabinet 10. As seen in Fig. 4, each shelf 33 has a portion thereof cut away to allow passage around the sprocket 35 after the ejector has returned to full line position and the chain conveyor is elevated to place a vendible article 25 in ejecting position 17' for the next operation.

At its normally lower end, the conveyor chain 34 is also trained over an idling sprocket 39 adjacent the normally lowermost bottom shelf 38 and disposed forwardly of a vertical line through 30 the upper shaft 31 so that the chain is inclined an amount corresponding to the inclination of the apron 20-21 which is positioned in front of the chain at a distance substantially equal to the width of a package. The sprocket 36 is 35 spaced from the sprocket 39 in the bottom of the cabinet and on the opposite side of the vertical line through the upper shaft 31, and there is provided a second idling sprocket 40 in the top of the cabinet and spaced horizontally from 40 the shaft 31. Thus a large number of merchandise packages may be stored, one above the other, on the shelving 33 with the topmost article 17' in view before the sight opening 12, and as articles are removed from the top of the column, 45 the conveyor chain 34 is moved upwardly by automatic mechanism now to be described.

The drive means, of which the sprocket 36 is a part, includes a driven sprocket 41 (Figs. 2 and 8) having driving connection through a 50 sprocket chain 42 to an electric motor 43. Also forming part of, or mounted for rotation with the gear 41 on shaft 49 is an insulated commutator block 44 on which is mounted a commutating ring 45 having a circuit breaking interruption 46 (Figs. 3 and 8), and against which normally bear a pair of spring contact fingers 47 and 48 (only contact 47 can be seen in the view of Fig. 8) arranged in circuit with the motor 43 in a manner hereinafter to be described.

60 The sprocket 41 and commutating ring 45 are fixed to a drive shaft 49 which extends across the cabinet 10 and which is common to each of the clutch operated intermediate drive means 36, there being one of these for each chain conveyor unit as illustrated in Fig. 6.

One side of the lower sprocket 36 is provided with a plurality of laterally projecting, annularly arranged rollers 73, each engageable by the teeth 74' and 74'' on a driven cam member 74 70 rotatably mounted, as at 75, on the bracket 71 (Fig. 7). A gear portion 76 of the cam 74 meshes with a similar gear 77 formed as a part of a sprocket unit 78 (which includes a pawl engaging ring 79 of the clutch member 80), Figs. 6 75 and 8. The gear 77, sprocket 78 and clutch ring

79 float on the drive shaft 49 and are normally at rest unless put into operation in a manner to be presently described.

The clutch 80 includes a collar 81 which rotates with the drive shaft 49 and carries a pin 5 82 upon which is pivotally mounted a pawl 83, the dogging end 84 of which is urged outwardly away from the shaft 49 by a spring 85. The nose 84 of the pawl is engageable in a notch 86 formed in the inner peripheral wall of the ring 79 and 10 is normally held out of such engagement by an arm 87 which pivots the pawl 83 (clockwise, Fig. 8) against the action of spring 85, by its engagement with a laterally extending pin 88 carried by 15 the pawl 83.

The clutch operating mechanism consists of a lever 89 pivotally mounted at 90 on a wall member. The arm 87 is a part of the lever 89 which has another arm 87' releasably engaged by a spring urged latch lever 91, which is likewise 20 pivoted to the wall member. The lever 89 is urged into latched engagement with the member 91, against the action of the spring 90' by a solenoid 92, the armature of which is linked to the arm 87', while the latch 91 is disengaged, 25 against the action of its spring, from the arm 87' by the armature of a trip solenoid 93.

Ejecting means includes ejecting cam 29 driven by a sprocket 51 (Figs. 4 and 5) over which is 30 trained a sprocket chain 52 driven by the sprocket gear 78 which is rotated with the clutch means 80 and driven sprocket 41. At each operation of the arm 25 from full to dotted line position (Fig. 5) the arm 25 engages an extended pin 35 of a switch element and causes a switch 53 mounted in the cabinet 10 to be put into circuit completing position.

The motor control circuit shown in Fig. 3 includes a plurality of coin switches 55 (one for 40 each bank of merchandise) connected by conductor 56 through the primary coil of a transformer to energize the solenoid 93, and thence to the motor 43. The conductor 57 is connected to one terminal 58 of a power source, the opposite side of the motor 43 being directly connected by conductor 59 to the other terminal 60 of the power source. Contact fingers 47 and 48 are connected in shunt around the switch 55 and are effective to bridge the latter through 50 engagement with the commutator ring 45.

Coin switch 55 (Fig. 2) is arranged at the discharge end of a coin chute 61 having communication through a conduit 62 with the coin deposit opening 16 of the particular column in the front of the cabinet. As deposited coins are discharged from the coin chute 61 down the discharge chute 63 toward a receptacle 64, they transiently engage a pivoted switch operating finger 65 and momentarily close the master coin switch 55 so as to complete a circuit through the line through solenoid 93 and motor 43, the switch 55 remaining operated long enough to permit the motor to pick up and drive the sprocket and commutator ring a distance sufficient to move the open circuit portion 46 of the commutator ring (Fig. 7) off of the contact fingers 47 and 48 to permit the latter to be bridged by the commutator ring 45, thus completing a shunt circuit around the master switch 55, so that when 60 the latter opens after the coin has passed the operating finger 65, the motor will continue to run until the commutator ring is turned through a complete revolution so as to position the interruption 46 therein again in the position shown 65 70 75 78 80 85 90 95 98 100 102 104 106 108 110 112 114 116 118 120 122 124 126 128 130 132 134 136 138 140 142 144 146 148 150 152 154 156 158 160 162 164 166 168 170 172 174 176 178 180 182 184 186 188 190 192 194 196 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 999 1000

in Fig. 3 to open the circuit through the wiper fingers 47 and 48 and stop the motor.

During this cycle of movement, the solenoid 93 causes the latch 91 to release the lever 89 for movement by the spring 90' out of engagement with the pin 88, thereby permitting the pawl 83 to engage its nose 84 in notch 86 of the clutch ring 79. The ejecting means for the particular column of merchandise chosen by the vendee is thereupon put into operation, the sprocket 78 by chain 52 rotating the cam 29 to operate the ejector 23. When the ejector returns to normal (full line, Fig. 2), the first tooth 14' of the cam 74 (Fig. 7) will begin to engage one roller 73 of the sprocket 36, moving the latter half its distance; the second tooth 14'' engaging the next roller 73 to move the sprocket 36 its remaining distance, whereupon the chain 34 will have lifted an article of merchandise into vending position 17'.

The movement of the arm 25 into dotted position and its engagement with switch 53 completes a circuit through a transformer to solenoid 92, which when energized will pull up its armature and the lever 89 to again cause the latter to be latched by the member 91 and place the arm 87 in a position to prevent nose 84 of pawl 83 from acting to permit operation of unit unless again released by operation of a coin.

When the machine is serviced, the front panel 18 may be removed and the lower trays or shelves refilled.

It will be apparent that various rearrangements may be made in the specific embodiment described in detail herein for purposes of illustration, and it is intended that all such changes and all other modifications and rearrangements of the herein specifically described embodiment of the invention are to be included within the fair scope of the appended claims.

Having thus described my invention, what I claim as new and desire to protect by Letters Patent is:

1. In a device of the class described, an endless conveyor mounted for movement in a vertical plane and including serially arranged means thereon for positioning articles in columnar form one above another, means providing a discharge chute positioned adjacent the top of a column 50 of merchandise on said conveyor, and a movable ejector member also arranged at the top of the column of merchandise for movement into engagement with the topmost article to dislodge the same for movement into said discharge chute, 55 motor means and mechanism providing a driving connection between said motor means and said endless carrier and said ejector member and arranged and constructed to effect operation of said ejector to dislodge an article as aforesaid and thereafter move said endless carrier a distance to position the next succeeding article at the top of said column, and control means for energizing said motor means for the purpose aforesaid.

2. In a device of the class described, a continuous conveyor arranged for movement in a vertical plane and provided with serially aligned

article supporting means for supporting articles of merchandise one above another, a periodically movable ejector mounted adjacent the top of the column of articles and movable during each period of operation to engage the topmost article 5 and dislodge the same from said conveyor, and mechanism including a motor and driving connections between the same, said conveyor, and said ejector, for operating both of the latter in timed relation whereby to effect operation of said ejector and thereafter to effect movement of said conveyor a predetermined amount adequate to position the next succeeding article in position for engagement by said ejector, and control mechanism for said motor and arranged and constructed for operation to energize the motor for a predetermined time to effect a predetermined number of ejecting operations.

3. In a vending machine, means for movably stacking merchandise units one above another in an approximately upright column, means for moving said stacking means in steps upwardly so as to position the merchandise units successively at the top of the column, a housing for said machine and means providing a sight opening in said housing opposite said top of the column and through which only the topmost merchandise unit is in view at all times prior to dislodgment for delivery to the patron, means for ejecting said topmost unit from the column toward said sight opening, means for receiving the ejected unit and delivering the same to a position of access to the patron exteriorly of the housing, and drive mechanism for actuating said ejecting means in ejecting operation to eject one unit and subsequently moving said stacking means to position the next succeeding unit before the sight opening as aforesaid, together with means under the control of the patron for starting operation of said drive mechanism, and means for automatically 40 stopping said mechanism when one unit has been ejected as aforesaid.

4. In a vending machine, in combination, a housing having a display window in the upper portion thereof, merchandise stacking means including a continuous conveyor mounted to move in a vertical plane with its uppermost terminal positioned substantially opposite said display window, said conveyor including article supporting means arranged to support articles one above another with an article at said terminal in view of said display window, means for dislodging a displayed article at said terminal by movement of said conveyor in a direction generally toward said display window, means within said housing 55 positioned to receive a dislodged article and guide the same in gravitating movement to a position of access from the exterior of the machine, means for actuating said dislodging means for the purpose aforesaid and subsequently moving said conveyor a distance sufficient to position the next lowest article at said terminal in view of said display window, together with control mechanism for effecting operation of the actuating means as aforesaid.

WALTER A. TRATSCH.
